UNITED STATES PATENT OFFICE.

EDWARD A. LANGENBACH, OF CANTON, OHIO.

DESIGN FOR A MOLDING-PLATE.

SPECIFICATION forming part of Design No. 26,237, dated November 3, 1896.

Application filed September 23, 1896. Serial No. 606,787. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Metallic Molding-Plates, of which the following is a full, clear, and exact description, reference being had to the accompanying drawings, making part of this specification.

My invention relates to a new design for a molding-plate.

The design consists of a molding-plate of the configuration and ornamentation shown in the accompanying drawings, in which—

In the drawings, A denotes a strip of metal having its upper edge formed with a vertical flange a, the lower edge of said flange terminating in an outward swell or roll b, below which is a flat portion c, the lower edge of which extends inwardly at d and downwardly at e. The swell b is provided with straight and curved ornamental lines extending vertically and longitudinally. The oval portion e is provided with curved arched lines connected by circles at their lower ends, while inverted arched lines are arranged within and connected to the former lines. The edge e is ornamented with semispherical and elongated alternating knobs.

A molding-plate thus constructed and ornamented gives a very pleasing effect to the room in which it is used, it being very striking to the eye.

What I claim is—

The design for a molding-plate as herein shown and described.

In testimony whereof I have hereunto set my hand this 30th day of July, A. D. 1896.

EDWARD A. LANGENBACH.
